UNITED STATES PATENT OFFICE.

JESSE L. LONG, OF MANCHESTER, GEORGIA.

LOOM STOP-MOTION.

1,282,893.

Specification of Letters Patent. Patented Oct. 29, 1918.

Application filed September 14, 1917. Serial No. 191,384.

To all whom it may concern:

Be it known that I, JESSE L. LONG, a citizen of the United States, residing at Manchester, in the county of Meriwether, State 5 of Georgia, have invented certain new and useful Improvements in Loom Stop-Motions; and I do hereby declare the following to be a full, clear, and exact description of the invention, such as will enable others 10 skilled in the art to which it appertains, to make and use the same.

This invention relates to stop motion for looms.

The object of the invention is to provide 15 an improved form of stopping mechanism which is operative by any one of the treadles, when a treadle strap breaks to stop the loom. In carrying out the invention it is the intention to utilize the warp stop motion of 20 the loom, in association with the treadle operated mechanism, so that the machine will be stopped in the same manner as when a warp thread breaks.

In the embodiment which is hereinafter 25 described, the invention is applied to a machine which is provided with a drop wire stop motion, in which detectors or drop wires fall across a feeler bar which vibrates below the set of drop wires. The mechanism 30 of my invention operates against the same feeler bar, upon the breakage of a treadle strap and the consequent falling of the treadle, to cause the stopping of the machine.

With the above objects in view, and such 35 others relating to the details of construction, as may hereinafter appear, my invention will now be fully set forth and described, reference being had to the accompanying drawings.

In the drawings:

Figure 1 is a section through a loom showing the device in place thereon,

Fig. 2 is a vertical section on line 2—2 of 45 Fig. 1.

Fig. 3 is an enlarged detail view, and

Fig. 4 is a similar view showing the operative position of the device.

In Fig. 1 of the drawings the warp 1 runs 50 over the whip-roll 2 and through the detectors or drop wires 3 of the stop motion mechanism, and thence through the heddle frames 4. The heddle frames are controlled in the usual manner by means of the treadle 55 straps 5, whose lower ends are connected to the treadles 6, the latter being operated in

the usual manner by means of the cams 7 upon the cam shaft 8.

The stop wires or detectors 3 form a part of a wellknown warp stop motion, and operate upon the detector or feeler 9 which is mounted upon the rock shaft 10, so that as the shaft is oscillated the lower edge of the detector bar 9 swings in an arc below the rock shaft. 65

Supported upon a bracket 11 which is secured to a suitable fixed part of the frame of the loom, is a horizontally disposed rock lever 12 whose forward end extends to a point above the free ends of the treadles 6. 70 Said forward end of the rock lever 12 suspends, by means of an adjusting link 13 a substantially rectangular frame 14 which surrounds the whole bank of treadles 6, in such a manner that the sides and bottom 75 of the frame stand wholly free of the treadles when the latter are in normal arrangement, as best indicated in Fig. 2. The rear end of the rock lever 12 carries a vertical rod 15 in pivotal relation, the upper end 80 of the rod 15 projecting through the horizontal rest 16 of a bracket 17 which is also secured to a fixed point of the frame of the loom in proximity to the detector bar 9. The rod 15 is surrounded above the rest 16 85 with a stop collar 18 which is adjustably set by means of a screw 19 so as to limit the downward movement of the rod 15 by striking against the upper face of the rest 16. The upward movement of the rod 15 beyond 90 the limit determined by the collar 18 carries the free or upper end thereof into the path of movement of the detector bar 9, and therefore has the same effect upon the latter as would the dropping of one of the detectors 95 or drop wires 3.

In the operation of the above described mechanism, the frame 14 which normally stands free of the treadles 6 is caught by the downward movement of a falling treadle 100 which has been released by the breakage of one of the treadle straps 5. The weight of the treadle is such that it carries the frame 14 downwardly when it contacts the lower side of the latter, with the result that the 105 rock lever 12 is rocked upon its fulcrum to throw the rod 15 upwardly. As a result, the upper end of the rod intercepts the feeler bar 9, and stops its vibration, so that the warp stop motion is thrown into operation 110 in the same manner as when one of the detector wires 3 falls. Thus, I have provided

a simple mechanism for actuating the stop motion of a loom upon the breaking of a treadle strap, and I have found by the use of this mechanism that the bad cloth or 5 "seconds" from a loom will be reduced at least twenty per cent. The mechanism is particularly adapted to use on looms with three or more sets of harness, where, when one shade is dropped, two or more are left 10 to operate so that a lot of bad cloth is made. By the use of a drop partial stop motion, the number will be instantly stopped, and this manufacture of bad cloth prevented.

What I claim as my invention is:—

15 In a loom, the combination with the harness treadles, of a warp stop motion having a vibrating detector bar, a loom stop motion comprising a support fixed above the treadles and below the vibrating detector bar, re-

spectively, a rocking arm adjustably pivoted 20 to the support above the treadles, a rest on the loom frame below the vibrating bar, a rod pivoted to one end of the arm and working through the rest to be projected into the path of the vibrating bar, an adjustable collar on the rod and normally seated on the rest, a frame about the treadles having a threaded eye centrally thereof, and a hook 25 on the other end of the arm and having a shank adjustably engaged in the threaded 30 eye.

In testimony whereof, I affix my signature in the presence of two witnesses.

JESSE L. LONG.
